UNITED STATES PATENT OFFICE.

FLOYD H. THOMAS, OF MILAN, PENNSYLVANIA, ASSIGNOR TO INGERSOLL-RAND COMPANY, OF JERSEY CITY, NEW JERSEY, A CORPORATION OF NEW JERSEY.

FLUID-ACTUATED HAMMER TOOL.

Application filed June 20, 1925. Serial No. 38,435.

This invention relates to fluid actuated hammer tools in which the implement to which blows of impact are imparted by the reciprocating hammer may be of any desired form. The machine may be a sand rammer, coal pick, rock drill, or of some other type, in which the pressure fluid is controlled by a distributing valve or valves, but in the present instance the particular type of machine to which this invention relates has a main piston controlled exhaust, an inlet valve, and a compression relief valve controlling auxiliary exhaust ports.

The objects of the invention are to construct both the inlet and compression relief valves in a simple manner and enable both valves to be located in compact and easily accessible form in a convenient position with relation to the cylinder, preferably in a valve box at the rear end of the cylinder between the cylinder and back head, although the location may be varied as desired.

Another object of the invention is to make the machine easy to hold during operation.

To these ends the invention is shown in one of its preferred forms in the accompanying drawings, in which

Figure 1 is a longitudinal sectional elevation of so much of a fluid actuated hammer tool as will serve to illustrate the invention, this view being taken on the line 1-1 of Figure 2 looking in the direction of the arrows,

Figure 2 is a transverse top plan view on the line 2-2 of Figure 1 looking in the direction of the arrows,

Figure 3 is an enlarged sectional elevation taken on the line 3-3 of Figure 2 looking in the direction of the arrows with the exception that the valves have oscillated so that the piston is moving rearwardly instead of forwardly as shown in Figure 1.

Figure 4 is a sectional elevation taken through the inlet valve on the line 4-4 of Figure 2 looking in the direction of the arrows,

Figure 5 is a sectional elevation taken through the compression relief valve on the line 5-5 of Figure 2 looking in the direction of the arrows,

Figures 6 and 7 are views similar to Figures 4 and 5 with the valves and piston in

a different position corresponding to the position shown in Figure 3, and

Figures 8 and 9 are similar views showing a different position of the parts.

Referring to the drawings, the cylinder A is provided with the piston B having the head C and the forward extending shank D adapted to impart blows of impact to the shank E of a suitable implement. Pressure fluid, as for instance, compressed air, is supplied through the supply passage F in the back head G and the main exhaust H of the cylinder is in this instance controlled by the piston.

A supply passage J for fluid under pressure communicates at the port K with the forward end of the cylinder and suitable means are provided in accordance with this invention for controlling the distribution of pressure fluid to both the rearward and forward ends of the cylinder.

In the present instance, a valve box comprising the plate or block L, the separator or spacer O and the cover P is located between the cylinder A and the back head G, and the inlet valve Q and the compression relief valve R are located in this valve box.

The valve box plate L is formed with the inlet port S communicating with the inlet passage J leading to the forward end of the cylinder and is also provided with the inlet port T leading to the rearward end of the cylinder. The valve box plate L is also provided with the ports U and V which act as auxiliary exhaust ports. The ports S and U are connected by a cross passage W and the ports T and V are connected by a cross passage X and these cross passages as shown are in the form of grooves milled or otherwise cut in the plate L and they are covered over by the solid central portion Y of the separator plate O of the valve box.

The separator or spacer plate O of the valve box is suitably formed in this instance with rectangular valve chambers a and b in which oscillating valves Q and R are located. These valves may be in the form of rectangular plates tapering substantially uniformly in each direction from the median or central portions so that they will rock or oscillate and they may be provided with apertures c and d into which the guide pins e extend.

The valve box cover P is formed with the inlet ports f and f' controlled by the inlet valve Q and two auxiliary exhaust ports g and h communicating with the atmosphere 5 preferably at opposite ends of a diameter of the valve box cover P and these auxiliary exhaust ports or compression relief ports g and h are controlled by the compression relief valve R as it oscillates. Since the passage J in the cylinder of the machine communicates by means of the cross passage W with the relief port U which in turn communicates with the exhaust port g compression 10 in the forward end of the cylinder is relieved as the piston is moving on its forward stroke and likewise since the inlet port T for the rearward end of the cylinder communicates by the cross passage X with the relief port V which in turn communicates 15 with the auxiliary relief port h compression is relieved in the rearward end of the cylinder as the piston moves rearwardly.

In the operation of the machine, let it be assumed that the piston is moving on its forward stroke as indicated in Figures 1, 2, 4 and 5. As the piston was starting and before it reached and covered the free exhaust port H the forward end of the cylinder was at atmospheric pressure and consequently 20 there was atmospheric pressure under the opposite end of the inlet valve Q through the passage J and port S. After the piston has covered the free exhaust H compression in the forward end of the cylinder is relieved 25 through the passage J, port S, cross passage W, port U and thence out through the auxiliary exhaust g through the end of the compression relief valve R which is in the position indicated in Figure 5 since pressure fluid 30 under working pressure in the rear end of the cylinder maintains the compression relief valve R in the position closing the opposite auxiliary exhaust h.

When the piston overruns the free exhaust 45 H as indicated in Figures 6 and 7, the pressure in the rearward end of the cylinder is dropped and the live pressure fluid through the inlet port f' in the valve box on top of the inlet valve Q in combination with the 50 slight compression in the front end of the cylinder exerted upon the under side of the valve Q through the port S rocks the valve to close the cylinder inlet port T and open the port S communicating by the passage J 55 with the forward end of the cylinder so that the piston starts on its rearward travel. At the same time live pressure fluid is admitted through the inlet port S, cross passage W

and port U to the under side of the compression relief valve R at one end thus oscillating said valve to close the auxiliary exhaust g and open the auxiliary exhaust h communicating through the port V with the rearward end of the cylinder as indicated in Figure 7. When the piston in its rearward travel closes the main exhaust H as indicated in Figures 8 and 9, compression in the rearward end of the cylinder is thus relieved through the auxiliary exhaust port h.

I claim:

1. In a fluid actuated hammer tool, the combination of a cylinder and piston, a main piston controlled exhaust for the cylinder, a valve box centrally in line with the cylinder at its rearward end and having valve chambers located side by side, valve seats in said chambers arranged in substantially the same plane transverse to the axis of the cylinder, a valve box cover, two separate oscillating plate valves located side by side in substantially the same plane in said valve box chambers, one an inlet valve and the other an auxiliary exhaust valve, inlet ports for both ends of the cylinder in the valve seat of one valve box chamber controlled by the inlet valve, separate auxiliary exhaust ports in the valve box cover controlled by the auxiliary exhaust valve, and cross passages in the valve box connecting the said inlet ports with said auxiliary exhaust ports.

2. In a fluid actuated hammer tool, the combination of a cylinder and piston, a main piston controlled exhaust for the cylinder, a valve box centrally in line with the cylinder at its rearward end, said valve box including a valve block and a cover, valve chambers located side by side in the said block, valve seats in said chambers arranged in substantially the same plane transverse to the axis of the cylinder, two separate oscillating plate valves located side by side in substantially the same plane in said valve box chambers, one an inlet valve and the other an auxiliary exhaust valve, inlet ports for both ends of the cylinder in the valve seats of one valve box chamber controlled by the inlet valve, separate diametrically opposite auxiliary exhaust ports in the valve box cover controlled by the auxiliary exhaust valve, and cross passages wholly in the said valve block connecting said inlet ports with the respective auxiliary exhaust ports for each end of the cylinder.

In testimony whereof I have signed this specification.

FLOYD H. THOMAS.
